UNITED STATES PATENT OFFICE.

DONALD S. BARROWS, OF ROCHESTER, NEW YORK, ASSIGNOR TO THE SYMINGTON COMPANY, OF NEW YORK, N. Y., A CORPORATION OF MARYLAND.

TRUCK SIDE FRAME.

Application filed March 16, 1925. Serial No. 15,856.

This invention relates to side frames for railway car trucks and more particularly to such frames in which secondary stresses are minimized by the provision of non-rigid connections between members thereof.

The principal object of my invention, generally considered, is the provision of a truck side frame which is relatively light in weight and in which deleterious bending stresses in members thereof and secondary strains, particularly at the junction of said members, are minimized by the provision of non-rigid joints at such junctions.

An object of my invention is the provision of a strong and easily manufactured truck side frame in which the compression member is relatively stiff, the tension member relatively flexible, and the ends of said members are connected by means of keys passing through slots therein, provision being made for assembling said members under initial stress.

Another object of my invention is the manufacture of an efficient truck side frame composed of three main elements, a compression member, a tension member which may be single or double, and a strut for spacing intermediate portions of said members, the joints between all three members being of a non-rigid type whereby secondary stresses and undesirable bending in said members are minimized.

A further object of my invention is the provision of a novel method of connecting compression and tension members in a truck side frame whereby if a plurality of tension members is employed the stresses therein are equalized and provision is made for preventing loss of the connecting keys.

A still further object of my invention is the provision of a desirable and easily manufactured truck side frame in which a cast compression member, formed with integral depending bolster guide portions, is utilized, said member having journal boxes rigidly connected thereto and also provided with housing portions adjacent the ends thereof, said portions being slotted for the reception of keys for connecting said member to a tension member.

An additional object of the invention is the provision of a flexibly connected truck side frame especially adapted for minimizing secondary strains in the members thereof,

said frame generally comprising a cast compression member with slots in the ends thereof and integral depending bolster guide portions provided with perforated lugs, a tension member or members, the ends thereof being slotted and key-connected to the corresponding ends of the compression member, and a spacing or strut member, the lower face of which is curved for engagement with the tension member and the ends of which are formed as upturned perforated arms engaging and pin-connected with the perforated bolster guide portions.

Other objects and advantages of the invention having to do with the particular details of elements and combinations of parts, will become more apparent as the description proceeds.

In the drawings which have been chosen to illustrate certain embodiments of my invention:

Figure 1 is a side elevation with the parts thereof in section, showing a truck side frame constructed in accordance with my invention, and separable journal boxes bolted at the ends thereof.

Figure 2 is a sectional view taken on the line 2-2 of Figure 1, looking in the direction of the arrows.

Figure 3 is a sectional view taken on the line 3-3 of Figure 1.

Figure 4 is a partial side elevation of a truck side frame showing a modification.

Figure 5 is a section on the line 5-5 of Figure 4, looking in the direction of the arrows.

Figure 6 is a partial side elevation of a truck side frame showing a further modification of my invention.

Figure 7 is a sectional view on the line 7-7 of Figure 6, looking in the direction of the arrows.

Before attempting to describe the various embodiments of my invention in detail, it may be desirable to consider the underlying principles governing the construction of a truck side frame in accordance with my invention.

The usual side frame is in the form of a three panel truss without diagonal or web members in the middle panel. In theory a truss of this form centrally loaded would not require these web members because the supporting forces at one end would equal

those at the other and there would be no unbalanced shear in the middle panel to be transferred. Hence, the middle panel would theoretically retain its shape without distortion because of greater shear on one side than on the other. Practically, however, the sustaining forces are never exactly equal and there are longitudinal forces which would tend to distort the middle panel to one side or the other.

The clearance necessary for the end bolster and the bolster springs makes it impossible to complete the middle panel and the necessary resistance against unbalanced vertical forces must be provided for in the joints at the four corners of said panel. This is a condition affecting all side frames employing the usual bolster springs.

In the typical frame under consideration the upper member is continuous over the three panels and is in direct compression for its entire length. This compression produces a proportionate shortening in each of the three segments above the corresponding panels of the frame. The vertical members separating the panels are in tension under load and their length is therefore proportionately increased. The lower truss member is in tension throughout its length and therefore each segment thereof is lengthened under load.

During these simultaneous individual deformations as a whole the side frame under load changes in shape slightly so that the angles between various members thereof are altered. A superficial inspection will show that in the center panel the upper interior angles are changed from approximately right to obtuse angles, and the lower ones from approximately right to acute angles. In like manner, the three interior angles in each end panel are altered from their original angularities. It is obvious that in a frame without pin-connected joints the natural tendency of each angle to alter is resisted by the rigidity of the structure and therefore a bending stress is induced in each intersecting member at each panel point. Analyses of destruction tests of rigid side frame and inspection of these frames which have broken in fair service point to one or another of these local bending moments as the ultimate cause of failure.

So far the foregoing analysis has been based on the assumption that the load is applied to panel points and that no member of the frame has been obliged to function as a beam, in addition to carrying its direct stress due to truss action. In practice, the load is applied to the usual side frame over a part of the distance between the bolster guide portions so that the lower member below said portions and carrying the spring plank, has a partially distributed load in addition to direct tension. The effect of this load on

the usual integral type of side frame is to cause the carrying member to assume a deflection curve, which makes the strains on certain portions of the frame so much more acute.

According to my invention I propose to reduce these secondary or bending stresses which may be and are very apt to be the cause of failure in service, by substituting non-rigid for the rigid joints between the various members in the usual form of cast side frame.

In the drawings in which corresponding parts are designated by similar reference characters, and considering first Figures 1, 2 and 3, there is illustrated a truck side frame comprising a compression member 8 which is preferably an integral casting formed with depending bolster guide portions 9 and 11 and end portions 12 and 13. These end portions may be formed with integral journal boxes or, as illustrated in the drawings, may have substantially horizontal flanges or webs 14 and 15, respectively, adapted to receive bolts 16 and 17, for respectively connecting journal boxes 18 and 19 thereto.

As more clearly shown in Figure 2, the ends of the compression member are preferably formed with a plurality of housing portions or hoods 21 and 22 forming pockets 23 and 24 between the main portion of the compression member and the outwardly spaced webs 25 and 26, respectively, on each side of said compression member.

A slot is provided extending through each end of the compression member and intersecting the webs 25 and 26 as well as the main portion of the compression member. It will be seen that the outer portions of this slot are shallower or shorter than the inner portions, that is, the slots 27 and 28 through the webs 25 and 26, respectively, are shorter than the slot 29 through the main portion of the compression member. The purpose of this construction, as will be apparent from Figure 2, is to provide for the insertion and locking in place of a main key member 31. This key member, although preferably formed as illustrated, may be otherwise shaped and is shown connecting two tension members 32 and 33, respectively, to the compression member 8, but it is obvious that if desired, a single tension member might be used.

The lower face of the slots is preferably curved or dove-tailed for cooperating engagement with the curved edge 34 of an equalizer member or shim 35. Between the main key 31 and equalizer member 35 a tapered key or wedge member 36 is inserted for applying the initial stress to the connected members and locking the main key 31 in place by raising it above the lower edge of the housing portions 21 and 22, re-

spectively. The ends of the tapered key or wedge 36 may then be bent over, as shown at 37, whereby the parts are securely locked together. The key passes through corresponding slots 38 and 39 in the tension members and those portions of said tension members adjacent the outer ends of said slots are preferably enlarged or thickened, as illustrated at 41 and 42, for providing an increased bearing area on said key member 31.

The outer edges of the slots 27 and 28 through the webs 25 and 26 are preferably formed with bosses or rims 43 therearound and each of said rims preferably has extending therefrom a plurality of reinforcing flanges 44 and 45 which merge into the main body of the compression member and serve to strengthen the hooded portions thereof. The outer portions of the webs 25 and 26 are curved and extended to partially surround the curved ends of the tension members 32 and 33, as illustrated in Figure 1.

A strut, saddle or spacing member 46 is provided between the compression member and the tension members 32 and 33 for spacing intermediate portions thereof. Said strut 46 is provided with a central substantially horizontal web portion 47 preferably formed on its upper surface with a plurality of bosses 48 and a pocket 49 for connection with a spring plank. The lower surface of said strut 46 is preferably provided with a curved saddle portion 50 adapted to form a seat for the intermediate portions of the tension members. The seat portions are preferably formed by a plurality of spaced upright webs on flanges 51 and outer projections 51'. The saddle portion may be in the form of a parabolic curve or so proportioned as to give minimum fiber stress in the tension member under the normal vertical load.

The opposite sides of the seat forming webs 51 and projections 51' are preferably connected to longitudinally extending vertical flanges 52 which decrease in depth toward their ends, as illustrated in Figure 1. The central portions of these flanges are preferably strengthened by stiffening flanges or webs 53 extending transversely thereof and connecting them with the substantially horizontal web portion 47 of the strut.

Upwardly extending arms 54 and 55 are provided at opposite ends of said strut member, said arms being preferably channel-shaped like the central portion of the horizontal portion of the strut member. Said arms 54 and 55 preferably decrease in width toward their ends and the central web portions thereof may be provided with triangular openings 56 for decreasing the weight of the member.

The web 47 of the strut member is preferably relatively wide, as shown in Figure

3, for forming a support of relatively large area for the spring plank. The ends of the strut arms 54 and 55 are preferably perforated at 57 and 58, respectively, and supported between corresponding portions of the channel-shaped bolster guide members 9 and 11, respectively, preferably by means of pins 59 and 61. Although the main horizontal portion of the compression member 8 is also shown as channel-shaped with inwardly extending flanges or lips on the vertical sides of the channel, yet, as is obvious, the exact construction of this member is not essential provided it is efficiently designed.

The method for determining the location of the pivotal members or pins 59 and 61 is by analyzing the deformation of the various members of the side frame and determining those points on the bolster guide portions, the horizontal distance between which does not vary when load is applied to the side frame. It will be obvious that such points may be determined because the general compression in the compression member 8 will cause points on the bolster guide portions to approach each other, whereas the bending of said member will cause them to be pulled away from each other.

The effect of mere compression is approximately the same on all portions of the bolster guides, whereas the effect due to bending increases approximately in proportion to the distance from the main substantially horizontal portion of the compression member. From this it will be apparent that at a certain distance from the main portion of the compression member points will be found where the distance between the bolster guide portions is substantially constant under load. Such points are selected for the pin connection with the strut or saddle member 46. Considering the stresses on this strut member 46, it will be seen that the bending moment from the pressure of the spring plank thereon causes the arms to tend to move toward each other, whereas the direct tension on said member has the opposite effect so that the ends of said arms tend to remain at substantially the same distance apart and thereby stresses on the pin connections 59 and 61 are minimized.

By virtue of the connection between the tension members 32-33 and the strut member 46 allowing angular adjustment between said members, the strut and said tension members are limited to substantially only direct tension without any undesirable secondary bending stresses. The same is true at the connections between the ends of the tension and compression members as angular adjustment is permitted by virtue of the key connections at these points.

Referring to Figures 4 and 5 showing a modification of the construction illustrated in Figures 1, 2 and 3, it will be apparent

that there is no radical difference except in the connecting means between the tension members 32^a and 33^a and the compression member 8^a. In this modification no hooded portion surrounding the ends of the tension members is provided on the compression member, said tension members merely being connected to the main body of the compression member 8^a at both ends thereof by means of main gibbed keys 31^a. Said keys extend through slots 38^a and 39^a in the tension members and through a slot 29^a in each end of the compression member as in the previous modification. The lower wall of the slot 29^a is preferably widened to extend through the slots 38^a and 39^a, as illustrated in Figure 5, and is formed with dove-tailed or tapering pockets 62 and 63 into which corresponding wedges or tapered keys 64 and 65 may be driven after assembly of the parts. These wedges 64 and 65 may be applied in place by heating blocks of metal to a suitable temperature, driving them in place and upsetting them to fit said pockets and hold the compression and tension members in assembled relation under the proper initial stress.

A slightly different form of connection between the ends of the compression member 8^a and the journal boxes 19^a is shown in this modification in that said compression member is provided with downwardly and outwardly flaring webs or flanges 65 and 66 which overlie and are adapted for connection with corresponding portions of the journal box. Except for the foregoing there is no substantial difference between this modification and the previous one.

Referring to Figures 6 and 7, another modification is illustrated in which the only substantial differences with respect to the second modification just described, are that the ends of the compression member 8^b are wider than the saddle portions on the strut member 46^b so that the tension members 32^b—33^b are not parallel but are divergent outwardly, as illustrated in Figure 7. A gibbed key 31^b is employed as in the previous modification but the same is held in place, not by metal forced into dove-tailed pockets, but by an auxiliary key 67 which may be slightly tapered and have the ends thereof bent over at 68 and 69 after assembly of the parts, thereby preventing accidental loss thereof.

To assemble the various elements of the side frame according to my invention, the strut or saddle member 46 may first be connected to the compression member 8, the tension members inserted in place engaging the seat portions 51 of said strut member, and the ends of the tension member inserted in the hooded portions at the ends of the compression member, or adjacent said ends if no hooded portions are employed. The

initial stress in the members can then be secured by holding the tension members tightly against the strut member and applying the desired force to the ends of the compression member while the keys and wedges are inserted in place.

It will be apparent that in view of the foregoing a strong and economical side frame for railway car trucks may be provided, said frame being lighter in weight than heretofore for the same strength because deleterious and possibly critical bending stresses are eliminated by the provision of non-rigid joints between the various members thereof at places where angular deformation normally tends to occur. On account of the side frame being formed as three main parts, that is, the compression element, the tension element which may be single or multiple as desired, and the strut or separator element, fabrication of such a side frame is facilitated because of the avoidance of the necessity for manufacturing extremely large castings.

By virtue of the key connection between the compression and tension members with provision for equalizing the stresses in said tension members even though their lengths differ slightly, a side frame may be constructed in which all the parts carry their required loads very efficiently and the connecting members, such as the main keys and auxiliary keys or wedges, are prevented from loss either by overlapping portions of the hooded construction on the compression member or by gibs provided on the main key members themselves.

In the embodiments illustrated the tension members are shown as being twisted through approximately 90° from the central portions thereof to the end connections with the compression member but it is obvious that such construction is not essential although probably preferable from a manufacturing standpoint.

Having now described my invention, I claim:

1. A truck side frame comprising a cast compression member, a relatively flexible tension member, and means intersecting the adjacent ends of said members and connecting them with the formation of non-rigid joints therebetween.

2. A truck side frame comprising a cast compression member formed with slotted pockets in the ends thereof, a relatively flexible tension member formed with slotted ends engaging the pockets in the ends of the compression member, and means extending through the slots of both members for securely connecting them while allowing angular adjustment therebetween.

3. A truck side frame comprising a compression member formed with slotted pockets in the ends thereof, a tension member pro-

vided with slotted ends received in said pockets, and a key passing through said compression and tension members at each end thereof for securely connecting them.

5 4. A truck side frame comprising a cast compression member provided with slotted housings at opposite ends thereof, the outer slots being shallower than the inner slots, a relatively flexible tension member provided 10 with slotted ends engaged in said housings, keys extending through the slots in said compression and tension members, and wedges inserted under said keys for applying an initial stress on said members and moving 15 said keys beyond the lower edges of the slots in the outer portion of the compression member housing whereby loss thereof is prevented.

5. A truck side frame comprising a cast compression member formed with a plurality 20 of housings in each end thereof, tension members extending between corresponding housings in the ends of said compression member, the ends of said tension and compression members being formed with cooperating slots, a main key extending through 25 said slots and connecting said compression member to a plurality of tension members at the ends thereof, an equalizer extending between 30 housings in each end of the compression member, and a tapered key inserted between the main key and equalizer to apply the initial stress to the members and prevent loss of the main key.

6. A truck side frame comprising a cast 35 compression member, a relatively flexible tension member, the cooperating ends of said members being provided with corresponding slots, and a gibbed key inserted through corresponding slots in said members for uniting 40 them while allowing angular adjustment therebetween.

7. A truck side frame comprising a compression member, a tension member, said 45 members being formed with cooperating slots in the ends thereof and the compression member being dove-tailed adjacent the lower portions of the slots therein, a gibbed key inserted through corresponding slots in said members for connecting them and held in 50 place by rigid means inserted adjacent thereto.

8. A truck side frame comprising a relatively stiff compression member, a relatively 55 flexible tension member, a spacing strut between intermediate portions of said members, and means forming non-rigid joints connecting corresponding ends of the compression and tension members and connecting said spacing strut to said compression member.

9. A truck side frame comprising a relatively stiff compression member, a relatively 65 flexible tension member, a spacing strut between intermediate portions of said members, means intersecting the corresponding

ends of the compression and tension members to connect them with non-rigid joints therebetween, and non-rigid connecting joints between the spacing strut and the compression member.

70

10. A truck side frame comprising a compression member, a tension member, a spacing strut between intermediate portions thereof, the corresponding ends of compression and tension members being slotted, keys 75 extending through said slots and connecting said members, the adjacent portions of said compression and strut members being perforated, and means extending through corresponding perforations in said members 80 for connecting them.

11. A truck side frame comprising a compression member, a tension member, a spacing strut between intermediate portions of 85 said members, the cooperating ends of the compression and tension members being connected non-rigidly, said strut member having a curved saddle portion cooperating with the intermediate portion of the tension member, and means forming non-rigid connections between the ends of the strut member and adjacent portions of the compression member.

90

12. A truck side frame comprising a compression member with integral depending 95 bolster guide portions, a tension member, non-rigid connections between cooperating ends of said members, a spacing member between intermediate portions of said compression and tension members, said spacing member having a central portion forming a spring plank seat and saddle for the tension member, and upwardly extending arms non-rigidly connected to the bolster guide portions of the compression member.

100

13. A truck side frame comprising a cast compression member formed with depending bolster guide portions and hooded end portions formed with slots extending through the ends and hooded portions thereof, a tension member, the ends of which are received in said hooded portions of the compression member, and keys extending through compression and tension members for uniting the same.

110

14. A truck side frame comprising a cast compression member formed with depending bolster guide portions and hooded end portions formed with slots extending through the ends and hooded portions thereof, a tension member extending on either side of said compression member, the ends of each tension member being received in the hooded portions of the compression member, keys extending through the corresponding portions of the two tension members and compression member, the bearings for the keys in the hooded portions of the compression member being so arranged that said keys are placed in quadruple shear by the tension 130

115

120

125

members, and means extending between intermediate portions of compression and tension members.

15. A truck side frame comprising a cast compression member formed with depending bolster guide portions and end portions each formed with a plurality of housings, a tension member extending between corresponding housings in opposite ends of the compression member, the cooperating portions of said compression and tension members being slotted, keys extending through the corresponding slots in the tension and compression member, wedges inserted under said keys to place the tension and compression members under initial stress and force the keys beyond the upper edges of the outer housing portions of the compression member whereby loss thereof is prevented, and means spacing said bolster guide portions from the tension member.

16. A truck side frame comprising a cast compression member formed with hooded end portions providing housings for two tension members, two tension members extending between opposite ends of said compression member on opposite sides thereof, said compression and tension members being provided with corresponding slots, a key inserted through said slots in the respective members, an equalizer positioned beneath said key whereby tension members of slightly unequal length may be utilized, and a wedge member inserted between said key and equalizer to place the members under initial stress.

17. A truck side frame comprising a compression member formed with depending bolster guide portions and provided with slots extending through the ends thereof, two tension members extending between the ends of the compression member on opposite sides thereof, the ends of said tension members being formed with corresponding slots, and a gibbed key at each end of the compression and tension members extending through the slots of said members and supporting a tension member from the compression member at each side thereof.

18. A truck side frame comprising a cast compression member formed with slotted end portions, a tension member on each side of the compression member and formed with a corresponding slot in each end thereof, the slots in the compression member being dove-tailed in the lower portions thereof, a gibbed key extending through corresponding slots and uniting the two tension members with the compression member, and means for locking said keys in place inserted below said keys in the dove-tailed portions in the compression member.

19. A truck side frame comprising a cast compression member formed with depending bolster guide portions and hooded end por-

tions formed with slots extending through the ends and hooded portions thereof, a tension member the ends of which are received in said hooded portions of the compression member, keys extending through compression and tension members for uniting the same, and a strut engaging the intermediate portion of the tension member and non-rigidly connected to the bolster guide portions of the compression member.

20. A truck side frame comprising a cast compression member formed with bolster guide portions and end portions formed with slots therein, a tension member provided with slotted ends, keys extending through the corresponding portions of said compression and tension members for uniting the same, a strut provided with a curved saddle portion engaging the intermediate portion of the tension member and spacing it from the compression member, and pins intersecting the ends of the strut and corresponding bolster guide portions for connecting said strut and compression member.

21. A truck side frame comprising a cast compression member formed with depending bolster guide portions and hooded end portions formed with slots extending through the ends and hooded portions thereof, a tension member on either side of said compression member extending into a hooded portion of the compression member and formed with corresponding slots, keys extending through said slots for uniting said tension members with said compression member, and a strut provided with upstanding arms pin-connected to the bolster guide portions of the compression member and provided with curved saddle portions engaging said tension members and spacing them with respect to the compression member.

22. A truck side frame comprising a unitary compression member formed with depending bolster guide portions, a relatively flexible tension member, the ends of said members being apertured adjacent the points of connection therebetween and means extending through said apertures for connecting said members non-rigidly.

23. A compression member for truck side frames formed as a casting with integral bolster guide portions, the ends of said member being formed with transversely extending slots adapted to receive means for connecting it with the corresponding tension member.

24. A compression member for truck side frames comprising an integral casting formed with depending bolster guide portions, and hooded end portions formed with slots extending through said ends and hooded portions thereof for connection with the corresponding tension member.

25. A strut for spacing compression and

10 tension members in a truck side frame comprising an integral casting formed with a central portion, the upper face of which is provided with means for supporting the 5 spring plank and the lower face of which is provided with a curved saddle portion for cooperating with the tension member, said strut being provided with upstanding arms on the ends thereof for non-rigid connection with a compression member.

26. Spacing means between compression and tension members in a truck side frame comprising an integral member formed with a central portion and upstanding 15 arms, the upper face of the central portion adapted for supporting a spring plank, the lower face being curved for cooperation with a tension member, the ends of said upstanding arms being perforated for receiving 20 means for connecting the same with a compression member.

27. The method of connecting the compression and tension members in a truck side frame comprising forming the ends of 25 said members with registering slots, assembling said members in cooperative relation, passing a key through each set of cooperating slots, and forcing a wedge member adjacent the key in the corresponding slot to 30 provide initial stress in the members.

28. The method of connecting the compression and tension members in a truck side frame comprising carrying the ends of the tension member up inside a housing 35 portion on each end of the compression member, said compression and tension members being provided with cooperating slots, passing a key through said corresponding slots, and forcing said key up be-

yond the lower edge of the housing slot 40 whereby it cannot be displaced sideways.

29. The method of connecting compression and tension members in a truck side frame comprising forming the compression member with housing portions in the ends 45 thereof, forming slots through said housing portions and the ends of said compression member, forming the upper portions of the slots in the housing portions lower than the corresponding portions of the slots in the 50 compression member, forming corresponding slots in the tension member, inserting the ends of the tension member in the housing portions of the compression member, inserting a key through corresponding 55 slots in said members, and driving a wedge member below said key to force it against the ends of the tension member slots and provide initial stress in the members, and lock said key in place between the housing 60 portions.

30. The method of connecting compression and tension members in a truck side frame comprising forming housing portions in the ends of said compression member, 65 forming corresponding slots through the housing portions, compression member and tension members, inserting a key through said corresponding slots, inserting an equalizing shim member with a convex surface 70 engaging a corresponding surface on the compression member, and inserting a wedge member between said key and equalizing shim whereby the initial stress in both tension members will be substantially equal regardless of slight variations in length. 75

In testimony whereof I affix my signature.
DONALD S. BARROWS.
